UNITED STATES PATENT OFFICE.

FRANK DAVID SHOLIN, OF PORTLAND, OREGON.

BOOK REST.

Application filed January 13, 1927. Serial No. 160,902.

My invention relates to improvements in rests or racks for supporting books, magazines or like articles in open position, and it consists in the combinations, constructions 5 and arrangements herein described and claimed.

An object of the invention is the provision of a rest or rack of the character described which can be folded to relatively small size 10 when desired or extended more or less to accommodate books or papers of various sizes.

A further object of the invention is the provision in a rack or rest of the character described of adjustable clamping or retaining members which not only serve to maintain a book, magazine, or like article open but also to permit convenient and easy "turning" or manipulation of a substantial number of sheets of the book, magazine, or 20 like article at the place where such article is open.

A still further object of the invention is the provision of a rest or rack of the character described that is adapted when in any 25 possible adjustment thereof to hold an associated book, magazine, or like article firmly.

Other objects and advantages of the invention will be apparent from the following description, considered in conjunction with the 30 accompanying drawings, in which,

Figure 1 is a face view of the improved rack in an extended position,

Figure 2 is a section substantially along the line 2-2 of Figure 1,

Figure 3 is an edge view of the rack with its adjustable supporting means shown partially in vertical section,

Figure 4 is a face view of the rack folded to its smallest size,

Figure 5 is a section substantially along the line 5-5 of Figure 4, and

Figure 6 is a perspective view of the rack and its supporting means with the pivoted lateral clamping or retaining members thereof in vertical position.

The improved rack comprises a folding supporting frame having a back including an upright middle member 1. The member 1 preferably is a channel member having a 50 smooth front face and having its flanges turned rearwardly and inwardly as best seen at 2 in Figures 2 and 5, thus producing a vertical guide-way at the rear side of the member 1 in which the bar 3 may slide and thus be adjusted vertically for a purpose to be presently set forth.

The bottom or base of the holder frame comprises a pair of similar sections 4, each of which is channel-shaped and is disposed with its flanges turned upward. The rear flanges 4^a of the base sections 4 are connected adjacent to their inner ends to the lower end portion of the frame member 1 by pivot elements 5 which also serve to connect the lower ends of the inner end bars 6 of the lazy-tongs generally indicated at 7 to the lower end portion of the member 1, the lower end portions of the bars 6 being interposed on the pivot elements 5 between the flanges 4^a on the base sections and the front face of the member 1. The pivot elements 5 are located at the same level on the member 1 and are so spaced transversely of the member 1 that the inner ends of the webs of the sections 4 will be close to each other, if not actually in contact with each other, when the sections 4 are in their downwardly swung horizontal positions as shown in Figures 1, 2, 4 and 6, the inner end edges of the rear flanges 4^a of the base sections 80 being rounded off as shown at 8 and the inner end portions of the front flanges 9 of the base sections 4 being cut away at 10, whereby swinging movement of the base sections 4 from lowered horizontal positions as shown in Figures 1, 2, 3 and 6 to raised vertical positions as shown in Figures 4 and 5, is possible.

The upper end portions of the inner end bars 11 of the lazy-tongs 7 have longitudinal slots 12 through which extend the shanks of headed studs 13 which extend forwardly from the upper end portion of the member 1. The back of the holder frame also includes a pair of end bars 14 which have 95 their upper end portions connected by rearwardly extending pivot elements 15 with the upper end portions of outer end bars 16 of the lazy-tongs. The pivot elements 15 are headed studs, the shanks of which work in longitudinal slots 17 in the upper end portions of the bars 16 of the lazy-tongs. The lower end portions of the bars 14 carry rearwardly extending pivot elements 18 which are located at the level of the pivot elements 5 100 and connect the bars 14 with the lower ends of the outer end bars 19 of the lazy-tongs.

The bars 14 have forward extensions 20 at their lower ends of slightly greater length than the width of the base sections 4 on 110 which the outer end portions of the base sections 4 will rest when the lazy-tongs are

extended more or less and the base sections 4 are in their downwardly swung active positions as shown in Figures 1, 2, 3 and 6. The members 20 have upturned forward end portions 21 which cooperate with the bars 14 to brace the outer end portions of the base sections 4 against lateral swinging movements and also serve as supports for the bar-like supporting sections 22 of vertically swingable arms which comprise the vertically swingable clamping end sections 22. The sections 22 of the retaining bars are connected with the upturned members 21 by pivot elements 24 adjacent to the ends of the sections 22 and the opposite end portions of the sections 22 are off-set rearwardly at 25 and connected by the pivot elements 26 with the doubled portions 27 of the bar-like clamping sections 23. Each of the clamping sections 23 comprises in addition to the doubled attaching portion 27 a substantially straight relatively long rearward main clamping portion and a forwardly off-set shorter auxiliary clamping finger or clip portion 29. A movable extension 29^a is carried by each finger 29 to facilitate the clamping of the book leaves. All of the aforesaid pivot elements are parallel with one another.

30 The longitudinal edge portions of the aforesaid vertically movable bar 3 preferably are off-set forwardly as indicated at 3^a in Figure 2 to fit slidably between the flanges 2 and the web of the member 1 when the 35 major portion of the bar 3 is substantially flush with the flanges 2. The upper end portion of the bar 3 is bent forwardly and downwardly at 30. A pair of upper clamping arms 31 have their upper end portions 40 connected by the forwardly extending pivot elements 32 to the down-turned part of the bent upper portion 30 of the bar 3, the respective pivot elements 32 being located at the same level and being parallel with all 45 the aforesaid remaining pivot elements.

50 The supporting means for the holder frame may include a pair of horizontally spaced attaching spring ears 33 which extend rearwardly from opposite edges of the middle portion of the frame member 1 and have apertured parallel rear portions 34 straddling a forwardly extending arm 35 on a vertical eye member 36 and secured to the arm 35 by the bolt 37 and the nut 38.

55 The eye member 36 is disposed between the vertically spaced ears 39 at the forward end of a rod 40 which has its rearward end disposed in a horizontal socket 41 in a block 42 that is slidable on a post 43 and can be secured in adjusted position on the post 43 by the set screw 44. The ears 39 have apertures in alignment with the bore of the eye member 36 for the reception of the bolt 45 which is engaged by the thumb nut 46. The ears 39 have considerable resiliency and the

thumb nut 46 can be tightened to lock the ears 39 to the eye member 36. The lower end portion of the post 43 carries a clamp which may comprise a sleeve 47 adjustable on the post and secured to the post by the set screw 48 and a pair of vertically spaced arms 49 which extend laterally from the sleeve 47 and respectively may be disposed above and below an edge portion 50 of a table, a chair arm, or like support and secured to such support by a clamping screw 51 which is threaded through a vertical opening in the lower arm 49 and thus is adjustable toward and away from the upper arm 49. The clamping screw 51 preferably has a plate-like clamping head 52 that is adapted to contact flatwise with the under surface of the support 50 when the upper arm 49 rests on the upper surface of the support 50 and the screw 51 has been tightened.

It is intended that the friction between all the hereinbefore described cooperative pivotally connected parts shall be sufficient to prevent accidental displacement of such parts from adjusted positions with respect to each other without rendering adjustment of such parts difficult manually. In some instances, the cooperative pivotally connected parts may have means whereby they will be more securely locked in adjusted position, such means being exemplified by the bolt 37 and nut 38 and the bolt 45 and thumb nut 46.

When the device is in set-up position as shown to advantage in Figure 3, it can be adjusted within a considerable range so far as its effective size as a rack for books, magazines, and like articles is concerned and the holder frame also can be adjusted to support the book, magazine, or like article at various angles to the horizontal and to the vertical and in various positions in respect to a reader. When the holder frame is in extended position as shown in Figures 1, 2, 3 and 6, a book or magazine placed thereon will be firmly supported in an open position and both the upper clamping arms 31 and the pivoted lateral or side clamping members of the holder frame may be used at the same time to maintain the book or magazine open. The relatively long main clamping sections 28 of the side clamping arms are inserted under a goodly number of sheets of the book or magazine on the holder frame and the edges of such sheets as are not engaged by the main clamping sections 28 are confined between the clamping sections 28 and the forward shorter clamping fingers or clips 29 so that the book or magazine will be firmly supported in an open position and at the same time a substantial number of pages at each side of the place of opening of the book or magazine can be turned readily as the reader may desire. The side clamping or retaining arms are sectional as hereinbefore described and therefore are capable

of various adjustments in respect to the leaves of an associated magazine or book.

When the holder frame is fully folded as shown in Figures 4 and 5, it is compact and takes up but relatively little space.

From the foregoing description of the device, it will be apparent that such device has many beneficial features and will be of real value as a rack or rest for supporting books, 10 magazines, and like articles of various sizes in open position so that such articles can be easily read without discomfort to the reader when the reader is in a reclining position or any other usual position and that the hands 15 of the reader may be free for use in writing or for any other purpose. While this rest is shown mounted on a table, 50 obviously it may be mounted on any other suitable support.

Obviously, the invention is susceptible of embodiment in forms other than that which is illustrated in the accompanying drawings and I therefore consider as my own all such modifications and adaptations thereof as 25 fairly fall within the scope of the appended claims.

I claim:—

1. A rest of the character described including a holder frame having a back comprising a middle supporting member, a pair of end bars, extensible and contractile means connecting said end bars with said middle member, and a base comprising a pair of sections pivotally connected at their inner ends with the lower part of said middle member on the back so that said base sections may swing vertically substantially from the plane of said middle member to positions to extend substantially at right angles with said middle member, and vice versa, said end bars having forward extensions at their lower ends for supporting the outer end portions of said base sections when said base sections are disposed substantially at right angles with said middle member of the back, said forward extensions having up-turned front end portions, and retaining arms pivotally connected with said up-turned end portions of the forward extensions.

2. A rest of the character described including a holder frame having a back comprising a middle supporting member, a pair of end bars, extensible and contractile means connecting said end bars with said middle member, and a base comprising a pair of sections pivotally connected at their inner ends with the lower part of said middle member on the back so that said base sections may swing vertically substantially from the plane of said middle member to positions to extend substantially at right angles with said middle member, and vice versa, said end bars having forward extensions at their lower ends for supporting the outer end portions of said base sections when

said base sections are disposed substantially at right angles with said middle member of the back, said forward extensions having up-turned front end portions, and retaining arms pivotally connected with said up-turned end portions of the forward extensions, said retaining arms comprising bar-like supporting sections pivotally connected at their lower ends with the up-turned forward end portions of said forward extensions, said supporting sections of the retaining arms having rearwardly offset upper end portions, and bar-like clamping sections having doubled portions pivotally connected with the rearwardly offset upper end portions of the supporting sections and comprising substantially straight rearward main clamping members and forwardly offset shorter clamping finger members.

3. In a rest of the character described, a holder frame having a back including an upright middle bar, a pair of end bars, and lazy-tongs connecting the end bars with the middle bar, and a base comprising a pair of sections pivotally attached at their inner ends to the lower end portion of the middle bar of the back at the front of the latter, said base sections being swingable vertically, said end bars having forward extensions at their lower ends for supporting the outer end portions of said base sections when said base sections are disposed substantially at right angles with said middle member of the back, a pair of retaining arms pivotally supported on the forward ends of said forward extensions, a vertically movable bar supported on said middle bar of the back of the holder frame, said vertically movable bar having a forwardly and downwardly turned upper end portion, and a pair of upper retaining arms pivoted to the forwardly and downwardly turned end portions of said vertically movable bar.

4. In a rest of the character described, a holder frame including a back having an upright middle member, a pair of end bars, and lazy-tongs connecting the end bars with the middle member, said middle member having flanges at its longitudinal edges extending rearwardly and inwardly to produce a guide-way, a vertically slidable bar having its longitudinal edge portions disposed between said flanges and the body of said middle member of the holder frame back, said vertically slidable bar having a forwardly and downwardly turned upper end portion, a pair of retaining arms pivotally connected with the forwardly and downwardly turned end portion of said vertically slidable bar, and a base comprising a pair of sections pivotally connected with the lower end portion of said middle bar and swingable to and from positions to extend laterally at opposite sides of said middle bar substantially at right angles therewith.

5. In a rest of the character described, a holder frame including a back having an upright middle member, a pair of end bars, and lazy-tongs connecting the end bars with the middle member, said middle member having flanges at its longitudinal edges extending rearwardly and inwardly to produce a guide-way, a vertically slidable bar having its longitudinal edge portions disposed between said flanges and the body of said middle member of the holder frame back, said vertically slidable bar having a forwardly and downwardly turned upper end portion, a pair of retaining arms pivotally connected with the forwardly and downwardly turned end portion of said vertically slidable bar, and a base comprising a pair of sections pivotally connected with the lower end portion of said middle bar and swingable to and from positions to extend laterally at opposite sides of said middle bar substantially at right angles therewith, and means at the lower ends of said end bars of the back of the holder frame for supporting the outer ends of said base sections when said base sections are disposed substantially at right angles with said middle member of the back of the holder frame.
6. In a rest of the character described, a holder frame having a back including an upright middle bar, a pair of end bars, lazy-tongs connecting the end bars with the middle bar, and a base comprising a pair of vertically swingable sections pivotally connected at the inner sides of their inner end portions to the lower end portion of said middle bar, and means for adjustably supporting the holder frame including a post having a universal connection at its upper end with the middle member of the back of the holder frame and a clamp adjustable on said

post and detachably engageable with an edge portion of a table, a chair arm, or like support.

7. In a rest of the character described, a holder frame including an upright bar, a pair of horizontally spaced ears extending rearwardly from said bar, an eye member having an arm disposed between said ears, horizontal pivot means connecting said arms with said ears, a rod having a pair of vertically spaced ears straddling said eye member, a vertical pivot element connecting said ears with said eye member, a post, a block adjustable on said post and supporting said rod, and a clamp adjustable on said post and comprising a pair of laterally extending vertically spaced arms and a clamping screw carried by one of said arms and cooperable with the other arm to grip an edge portion of a table, a chair arm, or like support.

8. In a rest of the character described, a holder frame including an upright bar, a pair of horizontally spaced ears extending rearwardly from said bar, an eye member having an arm disposed between said ears, horizontal pivot means connecting said arm with said ears, a rod having a pair of vertically spaced ears straddling said eye member, a vertical pivot element connecting said ears with said eye member, a post, a block adjustable on said post and supporting said rod, a clamp adjustable on said post and comprising a pair of laterally extending vertically spaced arms and a clamping screw carried by one of said arms and cooperable with the other arm to grip an edge portion of a table, a chair arm, or like support, and means cooperable with said pivot elements to lock the parts that the pivot elements connect to each other when desired.

FRANK D. SHOLIN.
